UNITED STATES PATENT OFFICE

119,279

DESIGN FOR A BOWL OR SIMILAR ARTICLE

Robert A. May, Washington, Pa., assignor to
Duncan & Miller Glass Company, Washington,
Pa., a corporation of Pennsylvania

Application December 21, 1939, Serial No. 89,075

Term of patent 14 years

To all whom it may concern:

Be it known that I, Robert A. May, a citizen of the United States, residing at Washington, Pennsylvania, have invented a new, original, and ornamental Design for a Bowl or Similar Article, of which the following is a specification, reference being had to the accompanying drawing, forming part thereof.

In the drawing:

Figure 1 is a top plan view of a bowl showing my new design; and

Figure 2 is an elevational view of the bowl shown in Figure 1.

The dominant feature of the design is the particular fluted formation at the lower portion of the article, and while shown applied to a bowl said formation is intended to be applied to other similar articles.

I claim:

The ornamental design for a bowl or similar article, substantially as shown and described.

ROBERT A. MAY.
